UNITED STATES PATENT OFFICE.

RICHARD T. BASHER, OF GIROUX LAKE, ONTARIO, CANADA.

CAN-PIERCING TOOL.

1,407,830.

Specification of Letters Patent. Patented Feb. 28, 1922.

Application filed June 23, 1920. Serial No. 391,116.

To all whom it may concern:

Be it known that I, RICHARD T. BASHER, a subject of the King of Great Britain, residing at Giroux Lake, in the district of 5 Temiskaming, Province of Ontario, Canada, have invented certain new and useful Improvements in Can-Piercing Tools, of which the following is a specification.

This invention relates to devices for forming holes in the ends of cans containing liquids and semi-liquids through which the contents of the can may be poured. Holes for the purpose described should be as close to the side of the can as possible, should present no external burr nor any internal burr at the outer edge to interfere with the free flow of the contents of the can through the hole, and preferably should present an external lip to prevent trickling down the out- 10 side of the can when it is set down after part of the contents have been poured out through the hole, and the object of my invention is to devise a simple tool which will 15 produce holes possessing the characteristics hereinbefore set forth.

I attain my object by means of the constructions hereinafter described and illustrated in the accompanying drawings in which—

30 Fig. 1 is a plan view of the tool looking at the under side;

Fig. 2 a side elevation illustrating the tool in position for piercing a can;

Fig. 3 a side elevation, partly in section, 35 showing the tool in position after a hole has been pierced;

Fig. 4 a front elevation of the tool with the parts in the position shown in Fig. 3; and

40 Fig. 5 a plan view of part of the top of a can having a hole punched therein.

In the drawings like numerals of reference indicate corresponding parts in the different figures.

45 1 and 2 are handles pivoted together at 3 in an ordinary manner and provided with the opposed jaws 4 and 5. The jaw 4 is formed with laterally spread horns 6 adapted to engage under the bead at the top of 50 a can as shown in Figs. 2 and 3. The jaw 5 is formed with a piercing prong 7 movable by the operation of the handles to and from a position between and overlapping the points of the horns, that is to say, the horns 55 and the piercing prong are so arranged that the point of the latter passes a line joining

the ends of the horns. A hole will thus be readily pierced through the top of the can by pressing the handles together after engaging the horns with the head as shown in 60 Fig. 2, the prong resting on the top of the can.

It is desired, however, not only to pierce the hole, but, as hereinbefore stated, to eliminate the inside burr at the pouring edge of 65 the hole and also to form the pouring edge with an outwardly bent lip to facilitate the pouring. I obtain this result by making the space between the horns of substantially a V-shape, the V being inclined rearwardly 70 and downwardly, having reference to the position of the tool when piercing a can. The inner end of the piercing prong is also substantially V-shaped to enter the space between the horns. From this shaping of the 75 parts it follows that not only does the piercing prong pierce the lid, but also compresses the metal of the rim of the can into the V-shaped space between the horns, thus at this side of the hole flattening out the burr 80 formed by the piercing operation and forming a distinct lip as shown particularly in Fig. 5.

From the above description it will be seen that I have devised a tool which will satisfactorily attain the objects of my invention 85 as set forth in the preamble of this specification.

What I claim as my invention is:—

1. A can piercing tool adapted to punch 90 a hole adjacent the edge of a can rim comprising handles pivoted together and provided with opposed jaws, one jaw being formed with laterally spread horns and the other with a piercing prong movable by the operation of the handles from a position in front and away from the points of the horns to a position overlapping the points of the horns, the point of the prong being always forward of a line joining the points of the horns. 100

2. A can piercing tool constructed as set forth in claim 1 in which the space between the horns is substantially V-shaped, the inner side of the piercing prong being also substantially V-shaped to enter the space between 105 the horns.

Signed at Cobalt, Ontario, this 9th day of June, 1920.

RICHARD T. BASHER.
